UNITED STATES PATENT OFFICE

JOHN H. VOSS, OF BERWYN, ILLINOIS, ASSIGNOR TO RESERVE HOLDING COMPANY, OF KANSAS CITY, MISSOURI, A CORPORATION OF DELAWARE

AUTOMATIC TELEPHONE SYSTEM

Application filed December 24, 1928. Serial No. 328,089.

The present invention relates to automatic telephone systems in general, but relates more particularly to small systems of this character commonly known as private automatic exchanges. These systems are as a rule privately owned by individuals or corporations and are installed in factories or other establishments for providing local service between a small number of local telephone lines and for establishing connections over trunk circuits to the main office of the telephone company's net-work.

The object of the invention is to provide means whereby a minimum number of switching devices will be employed at the branch exchange for completing the desired telephone connections and which will enable the equipment in such exchanges to be manufactured very cheaply while retaining all of the features necessary for modern high-class and dependable telephone service.

One of the features of the invention relates to the improved circuit arrangements of a link circuit comprising a numerical forward selecting switch for connecting with a called line and a non-numerical line finder switch for finding the calling line.

Another feature relates to the circuit arrangements of an improved trunk finder which will enable the trunk finder to be used as a finder switch on outgoing calls and as a directly controlled connector switch on incoming calls.

A further feature relates to a group of common control relays which are common to more than one trunk finder and which control the trunk finders to complete the connection to the desired local subscriber's line.

Other features, including supervision on trunk calls and night service, are mainly improved circuit details and will, together with the ones named above, be explained herein-after, reference being had to the accompanying drawings which comprise Figs. 1 to 3, inclusive, and which show by means of the usual circuit diagrams a sufficient amount of apparatus used in systems embodying the features of the invention to enable the invention to be understood.

Fig. 1 of the drawings diagrammatically

shows two automatic substations A and A', together with their individual cut-off relays, and a common line relay LR which is common to all the subscribers' lines, and a finder connector link circuit. The line circuit of each subscriber's line terminates in the banks of the finders, such as the finder F, and in the banks of the connectors, such as the connector C. Near the bottom of Fig. 1 in the dotted rectangle is shown the individual cut-off relay for the attendant's station which is shown in Fig. 3.

Fig. 2 diagrammatically shows a two-way trunk circuit TC extending from a distant automatic exchange and terminating at the local exchange in the trunk finder TF, the banks of which are connected in multiple with the banks of the connectors, such as C, Fig. 1. Relay 186 near the bottom of Fig. 2 is a relay which is common to the trunk finders, such as TF, and which controls the starting leads to the trunk finders, as will be explained hereinafter. In order not to unduly complicate the drawings only one trunk circuit and one trunk finder has been shown. In case of two or more trunk circuits the "out" start conductor, such as conductor 177, would extend through to the second trunk circuit and terminate therein in an armature spring similar to armature spring 154. However, as shown in the drawings, the "out" finder start conductor terminates in a terminal 194 and is jumpered by jumper 195 to terminal 193. Jumper 195 is shown in this manner so as to designate the start circuit extending through two or more trunk circuits and back to terminal 193 which is connected to the common relay 186.

At CTR in Fig. 3 there is diagrammatically shown the common trunk relays which are common to the trunk finders, such as TF, and which relays are controlled by an attendant on incoming calls over the trunk circuits, such as TC, to directly control the operation of the trunk finders, such as TF, to connect with and ring the desired called line. The conductors 172, 174, 175, and 176 are common conductors extending to all of the trunk finders while the answer control conductor 173 is individual to a particular trunk

finder. A similar answer control conductor 173' is provided for another trunk finder and is diagrammatically shown directly above relay 224. The remainder of the apparatus shown in Fig. 3 is located at the attendant's cabinet. The answer lamp 203, the supervisory lamp 204, the release key RK, the answer key AK, and the night key NK are individual to the trunk circuit TC shown in Fig. 2. Similar answering and supervisory lamps as well as release and answering keys are provided at the attendant's cabinet for the other trunk circuits. Relay 207 is a relay common to all of the keys for controlling the buzzer 222 to signal the attendant. Near the bottom of the figure there is shown a group of conductors which extend through the keys associated with the second trunk circuit. Terminals 290 and 292 and jumper 291 diagrammatically show how the buzzer connection lead 268 is looped through the various trunk keys to control the circuit of the buzzer 222. At the extreme right of Fig. 3 there is shown the attendant's substitution phone which is of the so-called monophone cradle-type. The springs 221 and 222 are shown in normal position with the monophone resting on the cradle. These springs close when the monophone is removed from the cradle. The usual receiver and transmitter as well as the calling device CD are diagrammatically shown in the usual manner. At LK is shown the line key by means of which the attendant may call or be called in the same manner as a local telephone line. At 282 is shown the attendant ringer by means of which the attendant is signaled when called as a local subscriber. The attendant's cabinet consists of a flat-top cabinet on which is mounted the monophone and the various lamps and keys.

The automatic substations A and A' are similar to each other and each has the usual signaling, talking, and switch-controlling instrumentalities. The line circuits in which the lines of each substation terminate are all similar and each has an individual cut-off relay, such as cut-off relay 4.

The mechanism of the finders such as F and TF, and the connectors, such as C, is of the well-known rotary type, commonly used for rotary line switches, and wipers of which move in a forward direction only and remain in the position last used. The circuit details of the connector C are somewhat different from the finders in that a pair of off-normal springs are provided in order to return the connector to its normal, or home, position after each connection. The trunk finders are also provided with off-normal springs, the purpose of which is to cause the trunk finders to be returned to their normal positions before they are directly operated as a connector to complete a connection to a called line. In Figs. 1 and 2 wherever con-

ductors terminate in reference characters enclosed in a circle it will be understood that these conductors are to be connected to similarly marked conductors.

In the case illustrated, applicant has elected to show a system having a maximum capacity of nine local telephone lines and two trunk lines, although only one trunk line is shown. The equipment necessary for this exchange would be two finder connector links, such as shown in Fig. 1, and two trunk finders and trunk circuits, such as shown in Fig. 2. With this equipment it is possible to have two local and two trunk connections established at the same time, it being understood that the capacity of the finders and connectors could be readily increased for a larger number of lines if needed. In this case the finders and connectors would probably be 25-point switches and would have access to twenty-four local lines. In case the capacity was increased it would probably be advisable to increase the number of finder connector links.

Having briefly described the apparatus involved in a system of this type, a detailed description of the operation will now be given. For this purpose, it will be assumed that subscriber A wishes to obtain connection with subscriber A'. When the subscriber at substation A removes his receiver to initiate a call, a circuit is completed for the common line relay LR and the cut-off relay 4 as follows: from ground through the winding of relay LR, conductor 3, armature 7, through the calling substation loop, armature 5, and through the upper winding of cut-off relay 4 to battery. Cut-off relay 4 is so adjusted that when the circuit is closed through its upper winding alone, armature 6 is the only armature which is operated. Cut-off relay 4, therefore, may be considered as a two-step relay in that it operates only its armature 6 on its first step and its armatures 5 and 7 on its second step when a circuit is closed for its lower winding. Cut-off relay 4, therefore, operates its armature 6 in its first step and prepares a circuit for its lower winding which is closed when the finder finds the calling line.

Common line relay LR is operated over the above-traced circuit and closes a circuit for the finder start relay 15 as follows: ground by way of armature 41, armature 36 and its resting contact, and winding of finder start relay 15 to battery. Relay 15, upon energizing, at armature 33 closes a circuit for energizing differential relay 12; and at armature 34 prepares a testing circuit for stopping the finder on the calling line. Differential relay 12, upon energizing, at armature 25 closes a self-interrupting circuit for stepping magnet 23. Magnet 23 interrupts its own circuit and steps the wipers 8, 9, 10, and 11 in search of the calling line. When wiper 10 engages the bank contacts in which conductor

88 terminates, said wiper will encounter a battery potential which extends through the lower winding of cut-off relay 4 and the resistance R in parallel for energizing the lower winding of differential relay 12 and for energizing relay 13. Relay 12, being differentially wound, immediately deenergizes and opens at armature 25 the stepping circuit of magnet 23, thereby stopping the wipers of the finder on the line of the calling subscriber 5. Relay 13, upon energizing, at armature 26 closes a circuit for energizing relay 16. A circuit is also closed from ground at armature 26 for stepping magnet 24 but due to the high resistance 44, stepping magnet 24 is not operated. Relay 16, upon energizing, at armature 36 opens the start circuit to the slow-acting relay 15 at its resting contact, and at its working contact transfers the start lead 10 over conductor 80 to the next finder connector link. The start relay, similar to relay 15 in the next finder connector link, is also a slow-to-energize and slow-to-release relay and, therefore, this relay will not completely, 15 energize to start the next finder because the common line relay LR will deenergize and open the circuit of this relay before it can operate its armature. At armatures 37 and 38 relay 16 closes a point in the two talking conductors and also closes a circuit for line relay 17. At armature 39 relay 16 connects ground to test wiper 10 which extends by way of conductor 88 and armature 6 to the lower winding of cut-off relay 4, thereby completely energizing the cut-off relay through 20 its second step to cut off the circuit of the common line relay LR which thereupon deenergizes. At armature 39 the circuit through the upper winding of differential relay 12 is opened and at the working contact of armature 39 the lower winding of differential relay 12 and the winding of relay 13 are temporarily short-circuited. This short circuit prevents the reenergization of differential relay 12 and causes relay 13 to deenergize and open the original energizing circuit of relay 16. At armature 40 relay 16 closes a temporary locking circuit for itself 25 extending by way of armature 35. Relay 15, being slow to deenergize as well as slow to pull up, maintains its armature 35 in operated position for a short period of time or long enough to permit line relay 17 and release relay 18 to energize to maintain relay 16 locked up. The circuit for energizing line relay 17 may be traced as follows: ground by way of the lower winding of relay 17, armature 38, armature 28, line wiper 9, conductor 2, the calling loop at substation A, 30 conductor 1, line wiper 8, armature 27, armature 37, and through the upper winding of relay 17 to battery. Line relay 17, upon energizing, at armature 42 opens the normal short circuit around relay 18 and also closes an energizing circuit for relay 18 as follows: 35

ground by way of armature 42, winding of release relay 18, armature 68, and winding of stepping magnet 24 to battery. Stepping magnet 24 does not energize in this circuit on account of the high resistance of relay 18. 70 At armature 43 line relay 17 opens a point in the circuit of slow-acting relay 19. Release relay 18, upon energizing, at armature 45 prepares a circuit for switching relay 22; at armature 46 prepares a circuit for relay 19; at armature 47 also prepares a circuit for relays 19 and locking circuits for relays 20 and 21; at armature 48 prepares another point in the circuit for relay 19; and at armature 49 and its working contact completes the locking circuit for relay 16 before slow-acting relay 15 has had time to deenergize. 75

It will be noted that as soon as relay 16 energizes the calling subscriber receives the dial tone over the following circuit: dial tone lead by way of resting contact of armature 61 and said armature; armature 67, condenser C, armature 38, and thence over the calling loop as previously described. When the calling subscriber A hears the dial tone he may then dial the number of the desired subscriber's line; in this case, since the desired called subscriber is A', the subscriber will dial the digit 4. Responsive to the operation of the calling device CD at substation A the circuit of line relay 17 is interrupted for a plurality of times and said relay accordingly deenergizes and energizes a corresponding number of times. Each time line relay 17 deenergizes, a circuit may be traced for energizing slow acting relay 19 and stepping magnet 24 as follows: ground by way of armature 47, armature 59 and its resting contact, armature 46, armature 43, through armature 48 to slow-acting relay 19 to battery; another path extends by way of armature 46 and thence by way of the normally closed springs controlled by armature 42, armature 68, and winding of stepping magnet 24 to battery. 80

At the normally closed springs controlled by armature 42, relay 18 is short circuited, thereby rendering said relay slow to release. By the operation of the stepping magnet 24 the wipers of the connector C are rotated step-by-step until they come to rest in engagement with the fourth set of bank contacts, or in this case in engagement with the bank contacts in which the line of substation A' terminates. Slow-acting relay 19, upon energizing, at armature 51 opens a point in the circuit of switching relay 22 so that relay 22 85 will not energize while the test wiper 73 is passing over idle contacts; at armature 52 places another ground on the impulsing circuit in case relay 21 should be energized 90 while the test wiper 73 is passing over grounded contacts. Relay 19, due to its slow to release characteristics, maintains its armatures operated during the impulsing period. Off-normal springs 70 close responsive to the 95

100

105

110

115

120

125

130

first step of the wipers and provides an additional holding ground for relay 16 as well as preparing a circuit for returning the connector wipers to normal position after conversation.

- 5 The further operation now depends upon whether the line of substation A' is idle or busy. In case the line of substation A is busy in another connection, ground will be present 10 on the bank contacts engaged by test wiper 73 and a circuit will be closed for the busy relay 21 as follows: ground by way of wiper 73, armature 29, armature 51 and its working contact, resting contact of armature 65 and 15 said armature, and winding of busy relay 21 to battery. Relay 21, upon energizing, at armature 57 opens a point in the circuit of relay 20; at armature 58 opens a point in the circuit of switching relay 22; at armature 20 59 prepares a locking circuit for itself which will be closed as soon as slow acting relay 19 deenergizes; and at armature 61 substitutes busy tone for the dial tone whereupon the calling subscriber A is given the busy 25 tone over the circuit previously traced for giving the subscriber the dial tone. A short interval thereafter slow acting relay 19 deenergizes and at the normally closed springs controlled by armature 51 completes the locking 30 circuit for busy relay 21 as follows: ground by way of armature 47, armature 59 and its working contact, normally closed springs controlled by armature 51, armature 65, and winding of busy relay 21 to battery.
- 35 When the calling subscriber hears the well known busy tone he will replace his receiver thereupon opening the circuit of line relay 17. Line relay 17, upon deenergizing, at the normally closed springs controlled by armature 42 places a short circuit around release 40 relay 18 whereupon the latter relay after an interval releases. Relay 18, upon deenergizing, at armature 47 opens the locking circuit of busy relay 21 whereupon the latter relay 45 deenergizes. At armature 49 relay 18 completes a circuit for stepping magnet 24 as follows: ground by way of off-normal springs 70, armature 49 and its resting contact, interrupter springs of stepping magnet 24, armature 68, and winding of magnet 24 to battery. Stepping magnet 24 energizes over this 50 circuit and interrupts its own circuit to step the wipers of the connector switch C around to normal position or until the off-normal 55 springs 70 open, thereby opening the circuit of magnet 24. As soon as the off-normal springs 70 open the locking circuit of relay 16 is also opened and said relay deenergizes. All of the apparatus in the finder connector 60 co link is now in normal position and may be used for completing other calls.

It will now be assumed that the line of substation A' is idle when the wipers of connector C are operated in engagement therewith. 65 In this case the busy relay 21 will not be oper-

ated and when slow-acting relay 19 deenergizes a circuit may be traced for energizing the switching relay 22 as follows: ground by way of the lower winding of switching relay 22, armature 58, armature 45, resting contact 70 of armature 51 and said armature, armature 29, test wiper 73, fourth bank contact accessible to wiper 73, conductor 77, and through the lower winding of cut-off relay 84 to battery. Switching relay 22, upon energizing, at armatures 62 and 63 prepares a point in the ringing and talking circuit; at armature 64 grounds the fourth bank contacts engaged by wiper 73 in order to make the line of substation A' test busy to other switches; and for fully energizing cut-off relay 84 at armature 65 prepares a circuit for relay 21; at armature 66 completes a locking circuit for itself from ground at armature 47 through 75 its upper winding; at armature 67 disconnects the busy and dial tone leads; and at armature 68 opens a point in the circuit of stepping magnet 24 to prevent subsequent stepping of this magnet. The cut-off relay 84 is energized over the above circuit and at armatures 85 and 87 disconnects itself and the common line relay LR from the line conductors 81 and 82. At armature 86 a circuit is closed for grounding conductor 76 which terminates in the finder banks. 80

Since the calling subscriber A does not hear the busy tone he will dial ring the called subscriber A'. In order to dial ring the called subscriber, subscriber A operates his calling device in accordance with the dial ring digit which may be either the digit 2 or the digit 8. In case the calling subscriber uses the digit 2 to dial ring the called line the bell of the called subscriber's line would ring for only a short interval of time, while if the digit 0 was used the bell of the called line would ring for a predetermined longer period of time. In this manner it is shown that it is possible to have two parties on the same line and that they may be signalled by codes of either short or long ringing impulses. However, in this case since only one subscriber is shown assigned to a telephone line it is immaterial which digit is used to dial ring the called line. Responsive to the operation of the calling device the line relay 17 is again intermittently operated and again causes the energization of slow-acting relay 19. The slow-acting relay, upon energizing, at armature 50 completes a circuit for busy relay 21 which is now used as a ringing relay. The circuit for energizing the relay 21 may be traced as follows: ground by way of armature 50, armature 55, working contact of armature 65 and said armature, and winding of relay 21 to battery. Relay 21, upon energizing, at armature 57 completes a circuit for ringing the called subscriber A' as follows: from generator lead Gen. by way of the working contact of armature 57 and said 120 125 130

5 armature, armature 53, armature 62, wiper 71, conductor 81, through the called line ring-
er and back to conductor 82, wiper 72, armature 63, and armature 54 and its resting con-
tact to ground. A short interval after the
dialling impulses cease, slow acting relay 19
deenergizes and opens the circuit of relay 21
whereupon the latter relay also deenergizes.
In case the called subscriber does not imme-
10 diately answer the calling subscriber may
again dial ring the called line and again ring
the bell of the called station.

When the called subscriber A' answers by
removing his receiver during a non-ring pe-
15 riod or silent period a circuit may be traced
for energizing relay 20 as follows: from
ground by way of resting contact of arma-
ture 54 and said armature, over the previously
traced circuit, this time, however, including
20 the transmitter and receiver in bridge of the
line and including armature 57 and its back
contact through the lower winding of relay 20
to battery. Relay 20, upon energizing over
the above-traced circuit, at armatures 53 and
25 54 completes the talking circuit; at arma-
ture 55 opens a point in the circuit of relay
21 so that any further impulses will not
operate relay 21; and at armature 56 com-
pletes a locking circuit for itself extending by
30 way of grounded armature 47. Calling sub-
scriber A and called subscriber A' are now
connected and may talk over the talking con-
ductors which are shown in heavy lines.
Both subscribers receive their talking bat-
35 tery from the windings of line relay 17.

After conversation and when both sub-
scribers replace their receivers, relay 17 de-
energizes and again causes the deenergization
of sleeve relay 18. Relay 18, upon deener-
40 gizing, opens the locking circuit of relays 20
and 22 at armature 47 and also closes at
armature 49 the local circuit for returning
the connector switch wipers to their normal
positions. The release of the finder connec-
45 tor link is accomplished in the same manner
as previously described. All apparatus is
now in normal position and is made avail-
able for other calls.

Having described in detail the manner in
50 which a local connection is completed a de-
tailed description of the operation that takes
place when a local subscriber calls a subscriber
in the main exchange will now be given. In
making outgoing calls to the main exchange
55 the local subscriber must first prefix the digit
"0" before dialling the regular telephone
number of the main exchange subscriber's
line.

For convenience, it will now be assumed
60 that subscriber A desires to complete a con-
nection with a main exchange subscriber's
line and responsive to the removal of the re-
ceiver at substation A the common line relay
LR and cut-off relay 4 operate in the same
65 manner as previously described to cause a

finder to find the calling line. Assume that
the finder F in Fig. 1 is the finder to be used
and in case the wipers of the finder are rest-
ing on the line of substation A the finder will
immediately switch through in the same man-
ner as previously described. Responsive to
70 the subscriber A dialling the digit "0" the
connector C is directly operated in the
same manner as previously described to set
the wipers on the tenth set of bank contacts.
Now when relay 19 falls back shortly after the
cessation of impulses a circuit may be traced
75 for energizing switching relay 22 and start
relay 110 (Fig. 2) in series as follows: from
ground by way of the lower winding of
switching relay 22, armature 58, armature 45,
resting contact of armature 51 and said arma-
ture, armature 29, wiper 73, tenth bank con-
tact, conductor 75, normally closed springs
controlled by armature 188, "in" start conduc-
tor 178, armature 154 and its resting contact,
80 armature 135 and its resting contact, and
winding of start relay 110 to battery.
Switching relay 22 energizes and operates its
armatures in the same manner as previously
85 described.

In the trunk circuit TC, Fig. 2, slow-to-
energize relay 110, upon energizing, at ar-
mature 136 closes a circuit for energizing
90 differential relay 107; at armature 138
grounds night service control conductor 179
and prepares a temporary locking circuit for
switch-through relay 109; and at armature
139 prepares a testing circuit for stopping
95 the trunk finder when the trunk finder finds
the calling line and finder connector link.
Differential relay 107, upon energizing, at ar-
mature 125 closes a self-interrupting cir-
cuit for the stepping magnet 105 of the trunk
100 finder TF. Responsive to the operation of
the stepping magnet 105 the wipers of the
trunk finder are moved step-by-step in search
of the calling finder connector link. When
wiper 103 of the trunk finder TF encounters
105 the bank contact in which conductor 83 ter-
minates a circuit may be traced including
relay 14 in the finder connector link and re-
lays 107 and 108 in the trunk circuit TC as
follows: from ground on the tenth bank con-
110 tacts engaged by wiper 74 of the connector
C (Fig. 1), armature 60, lower winding of
relay 14, wiper 11, conductor 83, fifth bank
contact engaged by test wiper 103, arma-
ture 139, normally closed springs controlled
115 by armature 131, lower winding of differen-
tial relay 107, and through the winding of
relay 108 to battery. Relay 107, being dif-
ferentially adjusted, immediately releases its
armature 125 and stops the wipers of the
trunk finder on the engaged bank contacts
120 or in this case on the bank contacts in which
the line of substation A terminates. Relay
108, upon energizing over the above-traced
circuit, at armature 126 closes a circuit for
125 energizing relay 109. Relay 109, upon ener-
130

gizing, at armatures 127 and 128 completes a point in the talking circuit and also completes a circuit for energizing relay 111. At armature 129 relay 109 opens the circuit through the upper winding of differential relay 107 at its back contact and at its front contact connects ground to conductor 89 to maintain the line of substation A busy to other switches which have access thereto. At 10 armature 130 relay 109 completes a locking circuit for itself, extending from grounded armature 138; at armature 131 opens the circuit extending through the lower winding of differential relay 107 while maintaining the circuit for relay 108; at armature 132 opens a point in the circuit for stepping magnet 105; and at armature 135 opens the circuit of slow-acting start relay 110 at its resting contact and at its working contact transfers 20 the start lead to the next trunk circuit or to the common relay 186 in case the second trunk circuit is in use. The circuit for energizing relay 111 may be traced as follows: from ground by way of the normally closed springs controlled by armature 146, armature 128, resting contact of armature 119 and said armature, wiper 101, conductor 2, over the loop at substation A, conductor 1, wiper 100, armature 118 and its resting contact, armature 127, relay 111, conductor 170, and to battery at the main exchange. Relay 111, upon energizing over the above-traced circuit, at armature 140, completes a circuit for energizing release relay 112. Relay 112, upon 30 energizing, at armature 141 opens a point in the circuits of relays 115 and 116; at armature 142 completes a circuit for energizing slow-to-release relay 113; and at armature 143 completes a locking circuit for relay 109 before slow-acting relay 110 has had time to fall away. The circuit for energizing relay 113 may be traced as follows: from ground at the main exchange, conductor 171, normally closed springs controlled by armature 147, armature 142, and winding of relay 113 to battery. Relay 113, upon energizing over the above-traced circuit, at armature 146 prepares a point in the talking circuit; and at armature 147 completes a locking 40 circuit for itself independent of ground from the main exchange.

Returning now to Fig. 1 and when relay 14 was energized responsive to the trunk finder finding the finder connector link, relay 14 at 50 armatures 27 and 28 opens the circuit of line relay 17; at armature 29 includes the resistance 32 in the circuit of relay 110; and at armature 31 completes a locking circuit for itself from grounded armature 40. Line relay 17, upon deenergizing, at the normally closed springs controlled by armature 42 short circuits the release relay 18, whereupon the latter relay releases and opens the locking circuit of relay 22 and closes the local stepping circuit for magnet 24 for returning the

wipers of the connector C to their normal positions as previously described. When the wipers of the connector C are returned to their normal position the off-normal springs 70 open the locking circuit of relay 16 whereupon relay 16 and then relay 14 deenergize to render the local finder connector link available for use on other calls.

When the line of substation A is cut through to the main exchange by the operation of relay 113, Fig. 2, the line switch individual to this trunk line at the main exchange hunts for and connects with an idle first selector from which dial tone is transmitted back over the trunk line in the well known manner. As soon as subscriber A hears the dial tone the subscriber will dial the main exchange subscriber's telephone number and the automatic switches in the main exchange will respond thereto and complete the connection to the desired line. Talking battery is furnished from the connector in the main exchange for both the P. A. X. subscriber and the main exchange subscriber.

After conversation and responsive to the main exchange subscriber replacing his receiver, the connector in the main exchange, being a release-by-last-party connector, is prepared for release. When subscriber A replaces his receiver the circuit of relay 111 is opened whereupon said relay deenergizes and at armature 140 opens the circuit of release relay 112. Relay 112, upon deenergizing, at armature 142 opens the circuit of slow-to-release relay 113 and at armature 143 opens the circuit of relay 109. Relay 109, upon deenergizing, at armatures 127 and 128 opens points in the talking circuit; at armature 129 removes ground from test wiper 102 and conductor 89; at armature 132 prepares a circuit for magnet 105; and at armature 135 reestablishes the starting circuit for relay 110. The trunk circuit TC and the trunk finder TF are now in normal position, it being understood however, that the wipers of the trunk finder TF remain in engagement with the bank contacts of the line last used and do not at this time return to their normal positions. The trunk finder TF and the trunk circuit TC may now be used for completing other connections.

Having described the detailed operation which takes place when there is an idle trunk finder and an idle trunk circuit, a description will now be given of the operation which takes place in case all of the trunk finders and trunk circuits are busy when an attempt is made to extend a connection to the main exchange. It will now be assumed that subscriber A attempts to make an outgoing call when all the trunk circuits and trunk finders are busy. In this case the finder F and connector C are operated in the same manner as previously described responsive to the removal of the receiver and the dialling of the

digit "0". In this case, since all of the trunk finders and trunk circuits are busy, a circuit may be traced for energizing relay 22 of connector C and said common relay 186 (Fig. 2) 5 in series when slow acting relay 19 deenergizes after the cessation of impulses. This circuit may be traced as follows: ground by way of the lower winding of switching relay 22, armature 58, armature 45, armature 51, 10 armature 29, wiper 73, conductor 75, normally closed springs controlled by armature 188, conductor 178, armature 154 and its resting contact and armature 135 and its working contact in case the trunk circuit is busy on 15 an outgoing call to the main exchange or by way of armature 154 and its working contact in case the trunk circuit is busy on an incoming call, outgoing start conductor 177, terminal 194, through the jumper 195 indicating a chain circuit similar to armatures 154 and 135 in the second trunk circuit to terminal 193, and through the winding of relay 186 to battery. Relay 22 energizes in the same manner as previously described and 20 at armature 64 connects direct ground to conductor 75 for fully operating relay 186. Relay 186 is a slow-to-energize relay and when a circuit is closed through it in series with the lower winding of switching relay 22 25 relay 186 energizes only far enough to make the "X" contacts close at armature 190. Responsive to the closure of "X" contacts at armature 190 ground through resistance 191 is extended by way of the resting contact of 30 armature 189 and said armature, over conductor 167 to the tenth bank contact engaged by wiper 71 of connector C and then by way of armature 62, armature 53 and its resting contact, armature 57 and its resting contact, 35 and through the lower winding of relay 20 to battery. Relay 20, upon energizing over the above-traced circuit, at armature 56 completes a locking circuit for itself by way of grounded armature 47; and at armature 53 40 prepares a circuit for transmitting the busy tone to the calling subscriber. When direct ground is connected to conductor 75 by the operation of sleeve relay 22 relay 186 (Fig. 2) slowly pulls up its armature and at armature 188 completes a locking circuit for itself and at armature 189 and its resting contact opens the original energizing circuit of relay 20 and connects busy tone over conductor 167 to wiper 71 at its working contact. 45 The busy tone circuit may be traced from wiper 71 over the heavy talking conductor to the calling loop and back to ground and to the lower winding of line relay 17. Should any more local subscribers attempt 50 to make an outgoing call at this time the connector C would operate in the same manner as when a connection is completed to a busy local line because of the ground on conductor 75. Responsive to the receipt of 55 the busy tone the calling subscriber replaces his receiver and therefore releases the finder connector link in the well known manner. When the wipers of the connector C are rotated off of the tenth set of bank contacts ground is removed from the conductor 75 and relay 186 is permitted to deenergize. 60 Having described the detailed operation which takes place when a local subscriber calls a main exchange subscriber, the detailed description of the operation which takes place when a main exchange subscriber desires to be connected with a local P. A. X. subscriber will now be given. When the connector in the main exchange responsive to the main exchange subscriber dialling the 65 private automatic exchange number seizes a trunk line, say for instance, conductors 170 and 171, a circuit is completed for the A. C. relay 116 during the ringing period and for relay 115 during the silent period. The circuit for energizing A. C. relay 116 is closed from the generator at the connector over conductor 170, armature 141, winding of relay 116, armature 157, and condenser C³ to conductor 171. Relay 115 is bridged across the 70 trunk conductors in series with resistances 155 and 156 and operates when the trunk is seized. Due to the inclusion of the resistances 155 and 156 the ring-cut-off relay in the main exchange connector is not operated at this 75 time. Responsive to the operation of relay 116 said relay at armature 159 closes a locking circuit for its lower winding extending from grounded conductor 180 by way of armature 145; at armature 157 opens its original energizing circuit; and at armature 158 closes a circuit for lighting the answering lamp 203 as follows: from grounded spring 206 of release key RK, conductor 180, armature 158, conductor 181, answer lamp 203, conductor 261, resting contact of spring 213 and said spring, and through the winding of relay 207 to battery. Relay 207 energizes over the above-traced circuit and at armature 208 completes a circuit for operating the buzzer relay 222 as follows: ground by way of spring 219 and its resting contact, conductor 275 which is looped through springs similar to the spring assembly 219 in the answer key individual to the second trunk circuit, terminal 292, jumper 291, designating the chain circuit through the various trunk keys, terminal 293, conductor 268, interrupter spring 223 of the buzzer 222, winding of buzzer 222, and armature 208 to battery. Relay 115, upon energizing over the above-traced circuit, at armature 156 closes a circuit for energizing relay 114. Relay 114, upon energizing, at armature 149 completes a new bridge across the trunk circuit independent of armature 141; at armature 150 closes a circuit for energizing relay 113; at armature 151 opens the short circuit around the lower winding of relay 112; at armature 152 prepares a locking circuit for relay 109; at armature 153 120 125 130

prepares an energizing circuit for relay 117; and at armature 154 switches the trunk finder start lead 178 to the next trunk finder or to the common relay 186. Relay 113, upon energizing, at armature 146 connects up the lower talking conductor and at armature 147 prepares a locking circuit for itself.

When the attendant hears the buzzer signal and observes the lighted condition of the answer lamp 203 she will first remove her monophone from its cradle, thereby operating the cradle springs 201 and 202 and then operate the answer key AK associated with the trunk circuit TC. The closure of the cradle springs 202 closes a circuit for energizing line relay 230 as follows: ground by way of the lower winding of relay 230, conductor 270, resting spring of spring 280 and said spring, conductor 278, impulse springs of the calling device CD, transmitter, receiver, spring assembly 202, conductor 279, spring 281 and its resting contact, conductor 271, and through the upper winding of relay 230 to battery. Relay 230, upon energizing, at armature 253 opens a normally closed short circuit from around release relay 228 and also closes an energizing circuit for relay 228 which may be traced as follows: ground by way of armature 253, winding of release relay 228, normally closed springs controlled by armature 234, conductor 175, armature 124, and winding of magnet 105 to battery. The latter circuit is not completed at this time because relay 106 is not at this time energized. Responsive to the operation of the answer key AK spring assembly 216 substitutes ground at the monophone spring 201 for the ground at springs 205 of the release key RK; spring assembly 217 grounds lead 267 and the answer control lead 173 in order to energize relay 117 in the trunk circuit TC; at spring assembly 218 connects conductors 260 and 261 together independent of the night key NK; at spring assembly 219 opens the buzzer circuit at the back contact and at its working contact closes a circuit for energizing slow relay 229; and at spring assemblies 220 and 221 connects the talking conductors 184 and 185 to talking conductors 272 and 273. The circuit for energizing relay 117 may be traced as follows: from ground by way of the working contact of spring 201, working contact of spring 217 and said spring, conductor 267, armature 231, answer control conductor 173, armature 153, and through the lower winding of relay 117 to battery. Relay 117, upon energizing, at armature 160 connects the talking conductor 184 to conductor 171 and also closes a shunt circuit around the resistances 155 and 156 in order to operate the ring-cut-off relay in the connector in order to cut off the ring; at armature 161 closes a holding circuit for relay 114 independent of armature 156; at armature 162 completes a self-interrupting

circuit for magnet 105 in order to return the trunk finder TF to its normal or home position; at armature 163 completes a locking circuit for itself through its upper winding to grounded disconnect conductor 180; and at armature 165 prepares a circuit for lighting the supervisory lamp 204. A short interval after relay 117 is fully operated, slow-to-energize relay 229 in the common trunk relay group CTR is energized. The delay in the energization of relay 229 is made so as to prevent unnecessary clicks in the receiver circuit. At armature 250 relay 229 prepares a circuit for locking relays 224 and 225 and at armatures 251 and 252 closes the talking circuit to the attendant's substation.

The circuit for returning the trunk finder TF to its home position may be traced as follows: from grounded answer control conductor 173, armature 162, armature 144, armature 123, armature 132, off-normal springs 104, interrupter springs of magnet 105, and through the magnet 105 to battery. Magnet 105 intermittently operates over the above-traced circuit and returns its wipers to home position at which time the off-normal springs 104 will open. It will be noted that the upper winding of relay 106 is normally short circuited as long as the off-normal springs 104 remain closed but as soon as the off-normal springs 104 open, a circuit may be traced from grounded answer control conductor 173 over a portion of the previously traced circuit to armature 123 from whence it extends to the upper winding of relay 106 and through the interrupter springs of magnet 105 and winding of magnet 105 to battery. Relay 106 is energized over this circuit but due to the high resistance of relay 106 stepping magnet 105 is not energized. Relay 106 at armatures 118 and 119 prepares a circuit for ringing the called subscriber; at armature 120 connects the common test conductor 176 to wiper 102; at armature 121 completes a locking circuit for itself to grounded answer control conductor 173; at armature 122 prepares a circuit for switch-through relay 109; at armature 123 opens a point in the circuit for its upper winding as well as opening the circuit for returning the trunk finder to its home position; and at armature 124 completes the circuit for the release relay 228 in the common trunk relay group as well as prepares the impulse circuit for the trunk finder magnet 105. Magnet 105 is not energized in series with relay 228 on account of the high resistance of relay 228. Relay 228 in the common trunk relay group, upon energizing, at armature 245 prepares the impulsive circuit over common pulse conductor 175; at armature 246 prepares a testing circuit which includes switching relay 225; and at armature 247 prepares a locking circuit for relays 224 and 225.

The attendant now asks the main exchange

subscriber for the number of the desired local subscriber's line. Assuming that subscriber A is the desired subscriber, the attendant will therefore operate her calling device CD in accordance with the number of the line of substation A. In this case the line number of substation A is 5 and accordingly five impulses are transmitted from the attendant's calling device. When the attendant's calling device CD is moved off-normal the shunt spring assembly 283 closes and shunts the transmitter and receiver thereby closing a direct circuit for line relay 230 and during the return to normal the impulse spring 277 interrupts the circuit of relay 230 five times. Responsive to each interruption in its circuit relay 230 energizes a corresponding number of times and for each deenergization relay 230 transmits a ground impulse for operating magnet 105 as follows: ground by way of armature 242, armature 245, normally closed springs controlled by armature 253, normally closed springs controlled by armature 234, common pulse conductor 175, armature 124, and winding of magnet 105 to battery. By the operation of the magnet 105 the trunk finder wipers are operated step-by-step to the line of substation A. Each time line relay 230 deenergizes said relay at the normally closed springs controlled by armature 253 closes a short circuit around relay 228 so as to render this relay slow to release during impulsing, and at armature 264 transmits an impulse of current for energizing slow-to-release relay 227. At armature 243 relay 227 prepares a circuit for operating combined busy and ringing relay 226; at armature 244 maintains ground on the impulsing circuit independent of armature 242 in case relay 226 is operated while wiper 102 is passing over grounded contacts; and at armatures 248 and 249 opens the talking conductors extending to the trunk conductors 170 and 171 in order to prevent the main exchange subscriber hearing the dialling impulses.

Further operation now depends upon whether the line of substation A is busy or idle. If the line of substation A is busy ground on conductor 89 engaged by test wiper 102 causes relay 226 to energize over the following circuit: from grounded conductor 89 by way of test wiper 102, working contact of armature 120 and said armature, common test conductor 176, armature 243 and its working contact, and through the winding of relay 226 to battery. Relay 226 at armature 239 opens a point in the circuit of cut-off relay 224; at armature 240 opens a point in the circuit of the switching relay 225; at armature 242 removes ground from the impulsing circuit; and at armature 241 closes a locking circuit for itself including grounded test conductor 176 and armature 237. After a short interval of time, slow-acting relay 227 deenergizes and at armature

243 and its resting contact prepares a point in the circuit of switching relay 225.

The attendant is informed that the line of substation A is busy because the supervisory lamp 204 does not light. The attendant then informs the main exchange subscriber that line A is busy and if the main exchange subscriber wants to wait she may do so. Now when the called line becomes idle ground is removed from conductor 80 and test wiper 102, thereby causing the deenergization of relay 226. Relay 226 at armature 241 completes a circuit for energizing switching relay 225 and at armature 242 again applies ground for the impulsing circuit. The circuit for energizing switching relay 225 may be traced as follows: ground by way of armature 246, upper winding of relay 225, armature 240, resting contact of armature 43 and said armature, conductor 176, armature 120, test wiper 102, conductor 89, and through the lower winding of cut-off relay 4 and resistance R to battery. Switching relay 225, upon energizing, at armature 234 disconnects conductor 175 from relay 228 and substitutes the battery through resistance 233 for the battery through the magnet 105; at armature 235 completes a circuit for the switching relay 109; at armature 236 prepares the ringing circuit and a circuit for the ring-cut-off relay 224; at armature 237 connects ground to conductor 176 in order to make the called line test busy and fully operate the cut-off relay 4; and at armature 238 locks up through its lower winding to ground at armature 250.

In the trunk circuit TC, Fig. 2, switching relay 109 is energized over the following circuit: from ground at armature 235, common switch through conductor 174, armature 122, and winding of switch-through relay 109 to battery. Relay 109, upon energizing, at armatures 127 and 128 prepares a point in the talking circuit; at armature 129 prepares a point in the circuit for grounding test wiper 102 after relay 106 falls back; at armature 130 locks up to grounded local release conductor 183; at armature 132 opens a point in the restoring circuit of magnet 105; at armature 133 prepares a ground return circuit for ringing the called line; at armature 134 completes a circuit for lighting the supervisory lamp 204; and at armature 135 opens a further point in the circuit of start relay 110. The circuit for lighting the supervisory lamp 204 may be traced as follows: from ground by way of disconnect conductor 180, armature 45, armature 134, armature 165, supervisory lead 182, supervisory lamp 204, conductor 261, spring assembly 213, and winding of relay 207 to battery. By the lighting of the supervisory lamp 204 the attendant is informed that the called line is now idle and accordingly dial rings the called line. Responsive to the operation of the calling device CD, line relay 230 is again intermittent.

ly operated and again causes the energization of relay 227. Relay 227, upon energizing at armature 243 energizes relay 226 over the following circuit: ground by way of the working contact of armature 237 and said armature, armature 243 and its working contact and winding of relay 226 to battery. At armature 239 relay 226 connects generator GEN to the called line over the following circuit: from generator GEN, working contact of armature 239 and said armature, armature 236, common ringing conductor 172, working contact of armature 118 and said armature, wiper 100, conductor 1, through the substation ringer and condenser of line A, conductor 2, wiper 101, armature 119 and its working contact, working contact of armature 133 and said armature, to grounded disconnect conductor 180. Shortly after the dial ring impulses cease, slow-acting relay 227 deenergizes and opens the circuit of relay 226 which accordingly deenergizes. Relay 226, upon deenergizing, at armature 239 prepares a circuit for energizing ring-cut-off relay 224 when the called line answers. If the called line does not immediately answer the attendant can dial ring again and ring as many times as needed. When subscriber A answers during a silent period a direct current bridge is substituted for the condenser and ringer and accordingly the ring-cut-off relay 224 is energized over its upper winding and over the ringing circuit as previously traced to grounded disconnect conductor 180. Relay 224, upon energizing, at armature 231 opens the circuit of relay 106 and at armature 232 closes a locking circuit through its lower winding to grounded armature 250. Relay 106, upon deenergizing, at the working contacts of armatures 118 and 119 opens the ringing circuit and at the back contacts thereof completes the talking circuit and completes an energizing circuit for relay 111; and at armature 120 connects grounded armature 129 to test wiper 102. The circuit for energizing relay 111 may be traced as follows: ground at the main exchange, conductor 171, armature 146 and its working contact, armature 128, resting contact of armature 119 and said armature, wiper 101, conductor 2 through the receiver and transmitter at the called station A, conductor 1, wiper 100, armature 118 and its resting contact, armature 127, winding of relay 111, conductor 170, to battery in the main exchange. This battery and ground connection at the main exchange is furnished through windings of the so-called back-bridge relay in the connector switch. At armature 140 relay 111 closes a circuit for energizing relay 112 through both its windings in series. At armature 145 relay 112 opens the locking circuit of relay 116 and also opens the circuit of the supervisory lamp 204. Relay 116, upon deenergizing, at armature 158 opens the circuit

of the answering lamp 204 and also causes relay 207 to deenergize.

The operation which takes place in case the line is idle when initially called is the same as just described, with the exception that in such case busy relay 226 is not energized from the busy line and the supervisory lamp 204 is thus responsive to the operation of switch-through relay 109 which informs the attendant that the line is idle. The operation from here on is the same as previously described.

After the called subscriber answers the attendant may release from the connection by first restoring the answering key AK and then replacing the monophone on the cradle. By the restoration of key AK, ground at springs 205 is substituted for ground at springs 201 by means of make-before-break springs controlled by springs 216. At springs 219 the circuit of slow-acting relay 229 is opened whereupon said relay releases and at springs 220 and 221 the talking circuit to the attendant is opened. At spring 219 the circuit for buzzer 222 is again closed in case the attendant has not in the meantime operated another trunk key. Relay 229, upon deenergizing, at armature 250, opens the locking circuit of relays 224 and 225 and at armatures 251 and 252 opens a further point in the talking circuit to the attendant's telephone set. Responsive to the placing of the monophone on the cradle springs 201 and 202 are operated and springs 202 open the circuit of line relay 230 in the common trunk relay group. Line relay 230, upon releasing, opens and short circuits relay 228 which thereupon deenergizes. Relay 227 is momentarily operated at this time without any effect. The attendant's equipment and the relays in the common trunk relay group are now in normal position and may be used on other calls.

The main exchange subscriber and subscriber A may now converse as desired, the talking battery being furnished from the main exchange.

During the time the main exchange subscriber is connected with subscriber A the main exchange subscriber may inform subscriber A that a connection to another local subscriber is desired. In this case we will assume that the main exchange subscriber now wishes to converse with the subscriber A' and accordingly subscriber A will flash the attendant by depressing the switchhook at intervals. When subscriber A depresses the switchhook thereat the circuit for relay 111 is opened and therefore said relay deenergizes. Relay 111 opens the circuit of relay 112 which thereby deenergizes and at armature 145 closes a circuit for operating the supervisory lamp 204 and relay 207 to operate the buzzer as previously described. By the intermittent operation of the switchhook at

substation A relays 111 and 112 are intermittently operated to flash the supervisory lamp 204 to call the attention of such a call to the attendant. When the attendant notes 5 the flashing of supervisory lamp 204 she will again remove the monophone from the cradle and again operate the answer key AK. Responsive to the removal of the monophone from its cradle the line and release relays 230 10 and 228, respectively, are operated. By the operation of the answer key relay 229 is again energized and the attendant is again connected across the trunk. The main exchange subscriber or subscriber A informs the attendant that the main exchange subscriber 15 wishes to converse with subscriber A' after which the subscriber A replaces his receiver on the switchhook. The attendant momentarily depresses the monophone cradle 20 springs, thereby separating springs 201 and 202 from their switching contacts. With the answer key AK in operated position and the operation of springs 201 and 202 springs 201 therefore removes ground from the locking 25 conductor 183, thereby causing relay 109 to deenergize. Relay 109, upon deenergizing, at armature 127 opens the circuit of relay 111; at armatures 127 and 128 opens a point in the talking circuit; at armature 129 re- 30 moves ground from wiper 102; at armature 132 short circuits the upper winding of relay 106 and prepares the self-interrupting circuit for magnet 105; at armature 133 closes a circuit for energizing relay 116; and at 35 armature 134 opens a point in the circuit extending to the supervisory lamp 204. Relays 111 and 112 accordingly deenergize. The circuit for energizing relay 116 may be traced as follows: from ground by way of grounded 40 disconnect conductor 180, armature 133 and its resting contact, armature 164 and through the lower winding of relay 116 to battery. Relay 116 at armature 158 closes a circuit for lighting the answer lamp 203.

45 Responsive to the lighting of the answer lamp 203 the attendant releases the cradle springs causing springs 201 and 202 to engage their working contacts. At springs 201 the circuit is completed for stepping magnet 105 of the trunk finder to cause the trunk finder to return to its home position as previously explained. After the trunk finder is in home position the attendant now dials the telephone number of the line of substation 50 A' and the trunk finder is operated in the same manner as previously described to engage the fourth set of bank contacts in which the line of substation A' terminates. The operation from now on will be the same as 55 explained for the connections completed to substation A.

After conversation and in case the main exchange subscriber replaces his receiver first, all of the switches except the connector 60 in the main exchange release. The main ex-

change connector is of the well known release-by-last-party type and therefore maintains the trunk busy until the P. A. X. or local subscriber hangs up his receiver. When the subscriber A' or A, as the case may be, replaces his receiver, the circuit of relay 111 is 70 opened and said relay accordingly deenergizes. At armature 140 relay 111 opens the circuit of relay 112 and said relay deenergizes and operates the supervisory lamp 204 and 75 buzzer since in the meantime the attendant has released the key AK. Responsive to this signal the attendant throws the release key RK, thereby removing ground from conductors 180 and 183, causing the deenergization 80 of relay 109 and 117. Relay 109, upon deenergizing, at armature 129 removes ground from test wiper 102 and conductor 77. Relay 117 is made slow acting so as to insure the release of relay 109 before relay 117 can 85 release and connect ground to its resting contact at armature 116. Relay 117, upon deenergizing, at armature 116 removes the short circuit around the resistances 105 and 106, thereby causing the back-bridge relay in the 90 main exchange connector to return to normal position. The main exchange connector accordingly releases in case the main exchange subscriber has replaced his receiver and by this release the connector opens the circuit 95 of relay 115 which also deenergizes. At armature 156 relay 115 opens the circuit of slow-acting relay 114. Relay 114 deenergizes and opens the circuit of relay 113 at armature 150. When relay 113 returns to 100 its normal position the trunk finder and trunk circuit is made available for use on other calls. In case the P. A. X. subscriber releases first, relays 111 and 112 deenergize 105 thereby operating the supervisory lamp 204 and the buzzer 222. The attendant now operates the release key RK and releases the local connection as previously described. The back bridge relay in the connector is also deenergized and as soon as the main exchange subscriber replaces his receiver all 110 the switches in the main exchange will release in the well known manner.

From the foregoing description it can be plainly seen that if during the process of 115 setting up one call another call comes in, the attendant may release from the first call and attend to the second call by restoring the answer key of this trunk and operating the answer key of the other trunk. After completing the second call the attendant may return to the first call and then complete such desired connection.

Having described local incoming and outgoing calls a description of the operation 120 which takes place will now be given in which the P. A. X. subscriber calls the attendant's station. For this purpose it will be assumed that the substation A desires to call the attendant's station. The attendant, as will be 125

noted, is given a local telephone number which in this case is the number assigned to line 9 which terminates in the ninth bank contact accessible to the connector wipers 71, 72, and 73. Responsive to the removal of the receiver at substation A, the finder F is operated in the same manner as previously described to find the calling line after which subscriber A dials the digit 9, thereby operating the wipers of the connector C to engage the ninth set of bank contacts in which the conductors 90, 91 and 93 terminate. Switching relay 22 energizes over the following circuit: from ground by way of the lower winding relay 22, armature 58, armature 45, resting contact of armature 51 and said armature, armature 29, wiper 73, ninth bank contact, conductor 93, and through the left hand winding of attendant's cut-off relay 97 to battery. When switching relay 22 energizes said relay at armature 64 connects direct ground to the attendant's cut-off relay, thereby causing the full operation of said cut-off relay. Subscriber A now dial rings the attendant, thereby causing the operation of the ringer 282 at the attendant's substation. The ringing circuit extends from generator GEN at armature 57 over the wiper 71, conductor 91, through the ringer 282, conductor 90, wiper 72 to ground at armature 54. Responsive to the operation of the ringer 282 the attendant operates the line key LK, thereby directly connecting her substation with conductors 90 and 91 as soon as she removes the monophone from its cradle. As soon as the attendant removes the monophone from its cradle, a direct current bridge is closed across conductors 90 and 91 whereupon the relay 20 in the connector C energizes and completes the talking circuit. Both the attendant and subscriber A receive their talking current from relay 17. The attendant can disconnect from the circuit of the trunk by the restoration of the key LK in order to answer and supervise incoming trunk calls and then return to the local connection by merely operating the key LK. After conversation the release of the connection is the same as previously described.

The attendant can also initiate a call using the local finder connector links by removing the monophone from its cradle and by operating the line key LK. This operation causes the common line relay LR to operate and start an idle finder connector link to hunt for the attendant's line. The attendant's cut-off relay 97 is operated in its first step in series with the common line relay LR and is operated in its second step when the finder F finds the attendant's line. The attendant then operates the calling device in accordance with the number of the desired called line and the connector C is operated to complete the connection after which the attendant dial rings in the usual way.

Since in a system of this size the attendant is on duty only during certain hours of the day some kind of service must be provided in case some one of the local subscribers desires to work overtime and still be able to receive and initiate incoming and outgoing calls to the main exchange. In such cases the local subscriber will inform the attendant that he wishes to have his line set up for night service, or in lieu of such specific instructions a certain specified local subscriber's line may always be designated for night service and the attendant would therefore prepare such line for night service before leaving her position. Before the attendant leaves her position she will remove her monophone and operate the answer key associated with the trunk to be used for night service and listen in on the trunk to determine if the trunk is busy. If the trunk is idle the attendant operates the night key NK in order to seize the trunk. Responsive to the operation of the answer key AK relays 228, 229, and 230 energize as previously described and responsive to the operation of the night key NK a circuit is closed for energizing relay 115 and for grounding the night service control conductor 179. The circuit for energizing relay 115 may be traced as follows: ground by way of resistances 209 and 210, working contact of spring 211 and said spring, spring 220 and its working contact, conductor 184, winding of relay 115, armature 141, conductor 170, to battery through the line relay of the line switch at the main exchange. The line relay at the main exchange does not energize over the above traced circuit on account of the high resistance of resistances 209 and 210 and relay 115. Relay 115, however, energizes over the above-traced circuit and at armature 156 again causes the operation of relay 114. Relay 114 again causes the operation of relay 113 and at armature 153 closes a circuit for energizing relay 117 which may be traced as follows: from grounded cradle springs 201, springs 217, conductor 267, armature 231, conductor 172, armature 153, and to the lower winding of relay 117 to battery. Relay 117 at armature 162 again closes the circuit for restoring the trunk finder to its normal position and at armature 164 closes a circuit for energizing relay 116 by way of grounded disconnect conductor 180 and armature 133 as previously traced. At armature 158 relay 116 closes a circuit for lighting the answer lamp 203 in the same manner as previously described. After the trunk finder is returned to its normal position relay 106 is energized in the same manner as previously described after which the attendant dials the number of the party to be connected up for night service. In case the line is idle, switching relay 225 is energized when the trunk finder wiper seizes the line of the called subscriber and closes the circuit.

cuit for energizing the switch-through relay 109 in the trunk finder. Switch-through relay 109 accordingly energizes and locks itself to the grounded night service control conductor 179. The operation of relay 109 also 5 closes a circuit for lighting the supervisory lamp 204. By the lighting of the supervisory lamp the attendant knows that the line of substation A is now prepared for night service and since no means is provided for 10 the attendant to talk to such a line set up for night service the attendant can code ring such subscriber in such a manner as to inform the subscriber that his line is now connected up for night service. After this the attendant 15 restores the answer key AK and replaces the monophone on its cradle. The common control relays CTR are restored to their normal position in the same manner as previously described and relay 106 in the trunk finder also 20 deenergizes and completes a direct circuit from the line of substation A direct through to the main exchange. Relay 106, upon deenergizing, at armature 120 connects direct 25 ground at armature 129 to test wiper 102 so as to make the line set up for night service busy to other local lines. In this manner it can be seen that the line set up for night service can be called from the main exchange and 30 make main exchange calls but cannot complete any local connections. Responsive to the restoration of the answer key AK to its normal position the circuit of the answering and supervisory lamps 203 and 204 are opened 35 and accordingly the lamps are extinguished.

The subscriber A can now receive and make main exchange calls. In order to make a main exchange call subscriber A merely removes his receiver and listens for the dial tone from the main exchange and after receipt thereof dials the main exchange subscriber's telephone number without prefixing the digit "0" because his line is now in direct connection with the main exchange. The 40 operation of the switches in the main exchange is well understood and need not be explained.

Calls to subscriber A in the main exchange are completed to the line of substation A over 45 conductors 170 and 171 in the ordinary manner since this station is now connected up the same as any other main exchange subscriber. It is possible for other local subscribers to 50 make outgoing calls to the main exchange over the other trunk circuit (not shown) but no incoming calls can be completed over this trunk circuit because the attendant has 55 left her position.

Having described the invention, what is 60 considered new and is desired to have protected by Letters Patent will be set forth in the following claims.

What is claimed is:

1. In a telephone system, a trunk line, a 65 finder individual to said trunk line having a

home position but normally remaining in the position last used, means responsive to the initiation of an outgoing call over said trunk line for causing said finder to find the calling line, and means for automatically returning said finder to its home position responsive to the act of answering an incoming call over said trunk line. 70

2. In a telephone system, a trunk line, a finder individual to said trunk line having a 75 home position but normally remaining in the position last used, means responsive to the initiation of an outgoing call over said trunk line for causing said finder to find the calling line, means for automatically returning said finder to its home position responsive to the act of answering an incoming call over 80 said trunk line, and means effective thereafter for directly operating said finder to extend the incoming call to a called line. 85

3. In a trunk finder having a home position but normally remaining in the position last used, a stepping magnet, a circuit for automatically operating said magnet to cause the wipers of the finder to find a calling line, 90 a second circuit for automatically operating said magnet to return the wipers to their home position, and a third circuit for directly operating said magnet to move the wipers into engagement with a called line. 95

4. In a two-way trunk line terminating in one end in a trunk finder, the wipers of said trunk finder having a home position but normally remaining in the position last used, means for automatically operating said finder 100 to find a calling line on outgoing calls, means for automatically advancing the wipers of said finder to home position under predetermined conditions, and means for thereafter directly operating said finder to connect 105 with a called line on incoming calls.

5. In a combination finder and connector switch of the type in which the wipers move in a forward direction only, means for operating the switch as a finder on successive calls without restoring the wipers, and means for restoring the wipers when the switch is used 110 as a connector.

6. In a telephone system, subscribers' lines, a two way trunk, a finder switch individual to said trunk having access to said lines, said finder having a home position but normally remaining in the position last used, means including a stepping magnet for operating said finder to connect a line with said trunk 120 when the line is calling, and means including said stepping magnet for automatically operating said finder to its home position and for then directly operating said finder to complete a connection to said line when 125 the line is called.

7. In a telephone system, a trunk line, a finder individual to said trunk line, said finder having a home position but normally remaining in the position last used, means 130

- responsive to the initiation of an outgoing call for causing said finder to find and connect with the calling line, an attendant's cabinet, an answer key individual to said trunk line at said cabinet, and means responsive to the operation of said key when the attendant answers an incoming call over said trunk line for automatically causing said finder to return to its home position. 70
8. In a telephone system, a trunk line, a finder individual to said trunk line, said finder having a home position but normally remaining in the position last used, means responsive to the initiation of an outgoing call for causing said finder to find and connect with the calling line, an attendant's cabinet, an answer key individual to said trunk line at said cabinet, means responsive to the operation of said key when the attendant answers an incoming call over said trunk line for automatically causing said finder to return to its home position, and means effective thereafter controlled by the attendant for directly operating said finder to complete a connection with a called line. 75
9. In a telephone system, a trunk line, a finder individual to said trunk line, said finder having a home position but normally remaining in the position last used, means responsive to the initiation of an outgoing call for causing said finder to find and connect with the calling line, an attendant's cabinet, an answer key individual to said trunk line at said cabinet, means responsive to the operation of said key when the attendant answers an incoming call over said trunk line for automatically causing said finder to return to its home position, means effective thereafter controlled by the attendant for directly operating said finder to complete a connection with a called line, and means responsive to further impulses generated by the attendant for dial ringing the said called line. 80
10. In a telephone system, subscribers' lines, a link circuit including a finder switch and a connector switch, means responsive to the initiation of a call by a calling subscriber for operating said finder to connect said link circuit to the calling line, means for directly operating said connector to extend the connection to a called line, a combined busy and ringing relay in said connector, a busy tone source, means for operating said relay to connect the busy tone to the calling line in case the called line is busy, means for preventing the connection of said busy tone to the calling line in case the called line is idle, a source of ringing current, and means for thereafter operating said relay to connect said ringing current to the called line. 85
11. In a telephone system, a branch exchange and a main exchange, subscribers' lines terminating in the branch, means in the branch for completing local connections between said lines, a trunk line connecting the main and branch exchanges and terminating in a switch at the branch exchange, means for completing incoming calls to any of said lines over said trunk line and for extending outgoing calls from any of said lines to the main exchange over said trunk line and said switch, means for setting up one of said lines for night service by connecting it to said trunk line via said switch, means then effective for making said line busy to all other local lines, and means whereby said line can call only main exchange subscribers or can only be called by main exchange subscribers. 90
12. In a telephone system, subscribers' lines, a link circuit comprising a finder switch and a connector switch, means responsive to the initiation of a call by a calling subscriber for causing said finder to find the calling line, means responsive to directive control from said calling line for causing said connector to extend a connection to a called line, and means in the connector responsive to directive control from the calling line for dial ringing the called line. 95
13. In a telephone system, subscribers' lines, a link circuit comprising a finder and a connector switch both having access to said lines, means responsive to the initiation of a call for causing said finder to find the calling line, means responsive to impulses generated by the calling subscriber for operating said connector to extend a connection to a called line, and means in the connector responsive to further impulses generated by the calling subscriber for signalling the called subscriber in accordance therewith while said impulses are being received. 100
14. In a telephone system, subscribers' lines, a link circuit comprising a finder and a connector switch both having access to said lines, means responsive to the initiation of a call for causing said finder to find the calling line, means for transmitting a distinctive tone to the calling line as soon as the finder finds the calling line, means responsive to impulses generated by the calling subscriber for operating said connector to extend a connection to a called line, and means in the connector responsive to further impulses generated by the calling subscriber for signalling the called subscriber in accordance therewith coincident with the receipt of such impulses. 110
15. In a telephone system, a main exchange and a branch exchange, a plurality of two-way trunk lines interconnecting the exchanges, a trunk finder individual to each trunk line at the branch exchange, means for automatically operating said finders to find calling branch exchange subscribers' lines responsive to the initiation of outgoing calls from the branch exchange, and a group of relays common to said trunk lines for directly controlling said trunk finders to connect 115
- 120
- 125
- 130

nect with called branch exchange subscribers' lines on incoming calls from the main exchange.

16. In a telephone system, a main exchange and a branch exchange, a plurality of two-way trunk lines interconnecting the exchanges, a trunk finder individual to each trunk line at the branch exchange, means for automatically operating said finders to find calling branch exchange subscribers' lines responsive to the initiation of outgoing calls from the branch exchange, a group of relays common to said trunk lines, and means in said group for causing said finders to be directly operated to called branch exchange subscribers' lines, for causing said finders to seize and make busy the called lines, for ringing the called lines, for cutting off the ring when the called lines answer, and for causing said finders to switch through and connect the called lines to the trunk lines on incoming calls from the main exchange.

17. In a telephone system, a two-way trunk line, a switch terminating said trunk line, means for operating said switch as a hunting finder to connect a calling line with said trunk line, operator's equipment for transmitting impulses to said switch to operate the switch as a connector to connect the trunk line with a called line, and a circuit excluding the trunk line over which said impulses are transmitted.

18. In a telephone system, a trunk line connecting a branch exchange with a main exchange, a switch terminating said trunk line in the branch exchange, means for operating said switch as a finder in a branch to main exchange call, and attendant's equipment including a calling device in the branch exchange for directly operating the switch as a connector in the main to branch exchange call.

19. In a telephone system, a directly controlled connector switch for setting up connections to called lines, said switch normally standing in the position last used, and means including the stepping magnet of the switch for automatically advancing the switch to home position responsive to its being taken into use for a new call.

20. In a telephone system, a trunk line terminating in an automatic switch, said switch standing normally in the position last used, a branch of said trunk extending to an operator's position, means for signalling the operator when a call is received, and means for restoring said switch to home position responsive to the answering of the call by the operator.

21. In a telephone system, a trunk line extending from a main exchange to a branch exchange, a switch terminating said trunk line at the branch exchange, said switch standing normally in the position last used, operator's equipment at the branch exchange for han-

dling incoming calls over said trunk, and means included in said equipment for causing said switch to assume its home position.

22. In a telephone system, a trunk line, a switch terminating said trunk line, a branch of said trunk line extending to an operator's position, means for signalling the operator over said branch responsive to a call over the trunk line, a calling device at the operator's position for transmitting impulses to directly operate said switch into engagement with a called line, a relay in said switch operative responsive to subsequent impulses from said calling device for projecting ringing current out on the called line during each series of impulses, and a talking circuit including said trunk line and said switch in set position but excluding the branch extending to the operator's position.

23. In a telephone system, a main exchange and a branch exchange, trunks connecting said exchanges and terminating in switches at the branch exchange, subscribers' lines terminating in the branch exchange, an attendant at the branch exchange, subscriber controlled means for operating the switch of an idle trunk to connect the trunk with a calling line, means controlled by the attendant for operating the switch of a trunk over which a call has been extended from the main exchange to further extend the connection to a wanted subscriber's line, and means controlled by the attendant for operating the switch of an idle trunk to connect with an idle line, whereon calls originating on said line will be extended directly to the main exchange and calls originating at the main exchange will be extended directly to said line.

24. In a telephone system, a main exchange and a branch exchange, a trunk line connecting said exchanges and terminating in a switch at the branch exchange, subscribers' lines terminating at the branch exchange, means for operating said switch to set up a connection from a calling line to the main exchange via the trunk line, means for operating the switch to set up a connection from the main exchange to a wanted line, means for opening the connection at the termination of a call, means for operating said switch to set up a connection from the trunk line to a subscriber's line for night service calls from either exchange to the other, and means for preventing the opening of the night service connection at the termination of such calls.

25. In a telephone system, trunk lines connecting a main exchange and a branch exchange, a switch terminating each trunk line, means for operating said switches as finders in branch to main exchange calls, and common control means for operating said switches as connectors in main to branch exchange calls.

26. In a telephone system, trunk lines connecting a main exchange and a branch ex-

change, a switch terminating each trunk line, means for operating said switches to connect with calling lines in branch to main exchange calls, and a common control circuit for directly operating said switches to connect with wanted lines in main to branch exchange calls.

27. In a telephone system, trunk lines connecting a main exchange and a branch exchange, a switch terminating each trunk line, means for automatically operating the switch associated with an idle trunk to extend a connection from a calling line to the main exchange, and means for transmitting directive impulses to a switch independent of the associated trunk line to extend a connection from the main exchange to a wanted line in the branch exchange.

28. In a telephone system, subscribers' lines, a link circuit comprising a finder switch and a connector switch, means responsive to the initiation of a call for operating said finder to hunt for and connect with the calling line, means responsive to directive digits transmitted over the calling line for operating the connector to extend a connection to a called line, a source of alternating current, and means in the connector responsive to directive digits transmitted over the calling line for connecting said current source to the called line during the transmission of each digit.

In witness whereof, I hereunto subscribe my name this 21st day of December, A. D. 1928.

JOHN H. VOSS.
